UNITED STATES PATENT OFFICE.

ARCHIE JAMES FRAME, OF MIAMI, FLORIDA, ASSIGNOR OF ONE-HALF TO FRANK L FELIX, OF HARTFORD, KENTUCKY.

CARBURETOR.

Application filed January 3, 1922. Serial No. 526,741.

To all whom it may concern:

Be it known that I, ARCHIE JAMES FRAME, a citizen of the United States, residing at Miami, in the county of Dade and 5 State of Florida, have invented certain new and useful Improvements in Carburetors, of which the following is a specification.

My invention consists in a new and useful improvement in carburetors for internal 10 combustion engines and is designed to provide a carburetor capable of supplying two kinds of liquid fuel. It is so constructed that the fuel demand of the engine at low speeds is supplied by gasoline while at high 15 speeds the engine is supplied with a heavier fuel oil.

The improved features of my device are clearly illustrated in the carburetor disclosed in the drawings which show one specific embodiment of my invention, but it must be understood that I do not consider my invention limited to the details of construction illustrated in the specific embodiment shown and hereinafter fully described, 25 but refer for its scope to the claims appended hereto.

In the drawings:

Fig. 1 is a side elevation partly in section of a carburetor embodying my invention.

Fig. 2 is an end elevation partly in section, on the line 2—2 of Fig. 1.

Fig. 3 is a top plan view.

Fig. 4 is a horizontal section through 35 Fig. 1, on the line 4—4.

The carburetor disclosed in the drawings has the usual tubular mixing chamber M, the upper end M¹ of which is adapted to be attached to the intake manifold of the 40 engine in the ordinary manner. The chamber M is provided with the usual air intake passage M². Extending outwardly from the wall of the chamber M there are two wings M³ and M⁴ to which is bolted the duplicate 45 float chamber C by means of the bolts M⁵ which are screwed into the bosses C¹ and C² of the chamber C. This chamber C is provided with two compartments G and O designed to contain gasoline and a heavier 50 fuel oil respectively. Each of these compartments G and O is provided with the usual form of fuel supply conduit and a float-controlled valve for same. A removable top C³ is provided to close both compartments G and O. Supply conduits C⁴

and C⁵ lead from the compartments G and O respectively, and communicate with the common conduit C⁶. Communication between the two conduits C⁴ and C⁵ and the conduit C⁶ is controlled by a two-way plug 60 valve C⁷ the operation of which will be presently explained.

The lower end of the mixing chamber M is provided with a centrally disposed bore M⁶ into which is snugly fitted a fuel nozzle core D held therein by a screw-cap M⁷ and packing M⁸. This core D has a fuel conduit D¹ which when the core D is positioned registers with the conduit M⁹ through the wall of the chamber M, which communicates 70 with the conduit C⁶. Surrounding the upper end of the conduit D¹ is the nozzle D² within which is the needle-valve D³ which is adjustably mounted in the core D and provided with the operating handle D⁴ 75 which passes through the packing M⁸ and the cap M⁷ and is readily accessible at the bottom of the carburetor.

Upon the upper end of the core D there are mounted three guides D⁵ in which is carried the reciprocable fuel sprayer D⁶. The core D is spaced from the nozzle D² and the lower part of this sprayer D⁶ fits loosely about the nozzle D². The sprayer D⁶ is provided with a fuel conduit D⁷ located directly above the nozzle D² and having a constriction D⁸ therein. This conduit D⁷ flares abruptly above the constriction D⁸ and has in its top a wire-mesh screen D⁹.

Located in the upper part of the mixing chamber M, there is the vane E mounted upon the rock shaft E¹ suitably journaled in the wall of the chamber M. To one end of the shaft E¹ which protrudes from the wall of the chamber M there is attached the 95 crank-arm E². A bracket E³ fixed on the outside of the chamber M above this arm E² carries an adjustable pin E⁴ which is connected with the arm E² by a coil spring E⁵.

Mounted upon the outside of the chamber M below the shaft E¹, there is a plate E⁶ provided with a pintle E⁷ for the bell-crank lever E⁸. A link E⁹ connects the outer end of the arm E² with one arm of 105 this bell-crank lever E⁸, and a link E¹⁰ connects the other arm with one arm of the bell-crank lever E¹¹ pivotally mounted upon the top of the boss C² of the fuel chamber C. A link E¹² connects the other arm 110

of this bell-crank lever E^{11} with a crank arm E^{13} which is mounted upon the top of the valve-stem C^8 of the plug valve C^7 .

The parts are so proportioned and related 5 that when the vane E is in normal position closing one-half of the passageway through the mixing chamber M , the valve C^7 is positioned to afford communication between the conduit C^4 of the compartment G containing gasoline, and the conduit C^6 communicating with the fuel conduit D^1 .

The usual throttling elements M^{10} and M^{11} are provided in the mixing chamber M and the air intake passage M^2 , respectively.

From the foregoing description of the details of construction, the operation of my improved carburetor will be obvious. The carburetor in normal adjustment is adapted 20 to utilize gasoline as fuel. When the speed of the engine increases, the suction through the mixing chamber M causes the vane E to move against the restraint of the spring E^5 , thus assuming a vertical position and 25 increasing the opening in the upper or fuel discharge end of the carburetor. This movement of the vane E operates the valve C^7 by means of the connections above described, so that the gasoline fuel supply is cut off 30 and the heavy oil fuel is admitted. When the engine speed is reduced, the consequent reduction of suction through the mixing chamber M permits the spring E^5 to restore the vane E to its normal position and thus 35 cut off the heavy fuel oil supply and re-establish the gasoline supply. It will be seen therefore that I have provided means for determining the character of fuel supply, which is automatically responsive to the 40 status of the operation of the engine.

Not only does the status of the engine's action determine the character of the fuel but it also determines the adjustment of the fuel supply means. This adjustment is 45 made by the movement of the reciprocable

fuel sprayer D^6 which is responsive to the suction in the mixing chamber M . Normally this sprayer D^6 rests upon the nozzle D^2 which regulates the fuel supply. When the speed of the engine increases the suction, the 50 sprayer D^6 is caused to rise from the nozzle D^2 , thus causing the conduit D^7 to form a well between the nozzle D^2 and the constriction D^8 . The extent of the movement of the sprayer D^6 and the consequent depth 55 of this well, which is determined by the degree of suction, determines the amount of fuel supplied.

Having described my invention, what I 60 claim is:

1. A carburetor for an internal combustion engine provided with two float chambers, a valve controlling the outlets of said chambers, and a vane adapted to be actuated by the suction of the engine and provided with means adapted to operate said valve.

2. In a carburetor for an internal combustion engine, the combination of a plurality of fuel chambers; an outlet conduit 70 leading from each of said chambers; a valve adapted to open and close each of said conduits; a mixing chamber; a vane pivotally mounted in said chamber; and a series of cranks and links adapted to be operated by 75 the movement of said vane to operate said valve.

3. A carburetor for an internal combustion engine provided with a plurality of fuel supply means, means responsive to the 80 engine suction adapted to selectively determine the operation of said supply means, said carburetor being also provided with air supply means, and means actuated by the air supply adapted to control each of the 85 fuel supply means to proportion the fuel supply in proper relation to the air supply.

In testimony whereof I affix my signature.

ARCHIE JAMES FRAME.
